METHOD AND APPARATUS FOR DETERMINING THE LOCATION OF PRODUCING HORIZONS IN WELLS

Abraham J. Teplitz, Oakmont, Pa., assignor to Gulf Research & Development Company, Pittsburgh, Pa., a corporation of Delaware

Application April 10, 1945, Serial No. 587,532

8 Claims. (Cl. 250—83)

1

This invention pertains to a method of and apparatus for determining the position of water or oil producing horizons in a well by radiological means.

In the production of oil from wells, it is customary procedure to set casing in the well and to place opposite the producing formation a screen or strainer through which fluid may pass into the casing or the tubing string. Such a screen allows the formation fluids to pass into the well but tends to restrain sand or other solid matter from doing so. If sufficient formation pressure exists, the well fluids will flow through the screen and up the producing tubing to the surface. If insufficient formation pressure is available, a pump is usually installed in the tubing above the screen.

Many oil producing formations do not solely produce oil. The producing formation often is made up of a series of horizons, some of which are oil bearing and some of which are water bearing. If a screen is set opposite the entire length of producing formation, a mixture of oil and water may be produced and, moreover, this mixture may become emulsified so that separation is difficult. Moreover, the water is usually saline and highly corrosive, and in a pumping well represents an expensive and useless load. It is therefore important to determine the source horizons of the water and oil so that steps may be taken to shut off or seal the water producing horizons and produce only oil.

The incursion of water into oil wells represents one of the major sources of expense in the production of petroleum. The pumping of water, handling of emulsions, disposal of the water, and the corrosion resulting from the water, are all costly factors attending the operation of wells producing water along with oil. In some cases it has been possible to shut off the flow of water from the producing formation by mechanical and chemical methods, but a large number of such treatments have proved unsuccessful principally because of the inability to ascertain which portion of the formation was yielding the water.

The object of this invention is to provide a method of locating the sources of water entering a well from the producing zone, thus making it possible to apply suitable treatment in the particular interval where it is needed, with consequent opportunity for success in recovering water-free pipe line oil.

Another object of this invention is to provide a simple apparatus for locating the sources of water or oil entering a well from the producing zone.

2

A further object of this invention is to provide a method of determining the points of entry of water in a well in such a manner that treatment may be applied immediately without dismantling equipment in the well.

The objects are accomplished as set forth in the following specification, which also includes an example of apparatus for carrying out the method of my invention. Reference is made to the drawing in which:

Fig. 1 is a section of the earth showing one form of my apparatus in place in a producing well;

Fig. 2 is a record obtained from a radiological examination of the well screen employed in my invention;

Fig. 3 shows details of construction of a well screen which may be employed in my invention;

Fig. 4 is a transverse section of a well screen which may be employed in my invention;

Fig. 5 is a section through a form of wire which retains the active material used in my invention; and

Fig. 6 is a section through another form of wire which may be used to hold active material.

In general, my invention consists of setting, opposite the producing formation, a special screen or strainer coated with or impregnated with a water-soluble radioactive substance or mixture. After allowing the well to produce for a sufficient length of time, the screen may be examined either in place in the well or upon being brought to the surface. Examination is made by means of an instrument sensitive to emanations from the radioactive substance. It is evident that the lowest radioactivity will be found at the point or points where the most radioactive material has been dissolved away.

In one way of employing my invention, a well is completed by setting a strainer opposite the producing zone in the conventional manner. This is shown diagrammatically in Fig. 1 in which is indicated a well penetrating earth formations 1, 2, 3, 4, 5, 6, 7, 8 and 9. Formations 4, 5, 6, 7 and 8 are in the producing zone, but some of these

either initially or subsequently will produce water and some will produce oil. A casing 10 is cemented at 11. Equipment at the top of the well is not indicated since this is conventional. At the lower end of the casing 10 is suspended the strainer 14 with a conventional packer 15 which may be either an expansion type or a permanent seal.

Inside the casing and projecting into the strainer is suspended the production tubing 13. The strainer 14 is provided with the usual openings through its wall and along its length; these

openings being indicated by numeral 17. The strainer is further provided with grooves 18 cut in the outer face of the solid portion, said grooves being filled with a mixture consisting of a radioactive substance dissolved or suspended in a cement or plastic material which is soluble in water.

A simplified sketch showing the details of a strainer which may be employed is shown in Figs. 3 and 4. The pipe 23 containing perforations 24 and provided with separators 25, is wrapped with wire of the cross-section shown in Fig. 6 by 27, this wire having spacing lugs 28 which form the openings 31 which permit fluid to enter the inside of the strainer while restraining the entrance of sand and other solid particles. The upper part of the screen assembly is equipped with threads 29 for attachment with a suitable packing device and to the lower portion is fastened the set-shoe 30 containing a back pressure valve assembly which permits washing around the outside of strainer while preventing the entrance of formation cavings into the inside of the screen.

The radioactive material is contained in grooves 32 in the wire wrapping. Wire wrapping of suitable type is conveniently formed by running wire, which may be stainless steel or bronze, of the cross-section 26 shown in Fig. 5 through rollers designed to produce the spacing lug 28 (Fig. 6) and at the same time press in the outer edge making the groove 32 of a dove-tail shape which provides better retention for the radioactive material.

A suitable mixture for filling these grooves may be made by mixing plaster of Paris with about 10 per cent of its weight of finely ground carnotite and then adding sufficient water to make a pasty mass. This mass can then be thoroughly spread over the surface of a screen having wire of the cross-section indicated. After allowing sufficient time for the mixture to partially set, the opening at the bottom of the screen may be plugged and water pressure applied to the inside at the upper end thus washing the excess plaster out of the screen openings 31 and leaving the grooves 32 full of the radioactive material. The set plaster of Paris has a slight solubility in water (about 0.1 gram in 100 ml.) and will gradually be removed in the well by water moving past it.

Another method of forming the screen could be accomplished by incorporating a radioactive substance in a plastic, such as the polyvinyl alcohol resins which are manufactured with varying degrees of solubility in water depending upon the method of preparation. Such a mixture having considerable flexibility could be filled into the groove in the wire before the latter is wrapped around the pipe.

A considerable variety of straining devices are known to those familiar with oil-field practice but any of these may either be provided with recesses for retaining the radioactive material or be coated with radioactive material incorporated in a suitable binder or cement. It is desirable in some cases to incorporate a radioactive element into the screen wire itself, in which case the wire could be made of a magnesium alloy or other alloy having a slight solubility in water. Also instead of plaster of Paris, or plastic material, low solubility salts such as magnesium phosphate, lithium triphosphate, calomel, and thallium iodide may be used by first fusing the salt and dispersing the carnotite or other radioactive substance in the molten mass.

If the annular space between the strainer and

the well bore is large so that there exists the possibility that some of the fluid entering the well may pass vertically up or down the annulus before entering the strainer, this condition may be remedied by affixing barriers of metal, leather or other material to the outside of the strainer, causing the fluids to travel horizontally from the formation through the strainer.

After setting the strainer, the well is put on production in the usual manner. Later, when the well begins to produce appreciable quantities of water along with the oil, any suitable detector of radioactivity is lowered into the well. Such a detector, indicated by numeral 16 in Fig. 1, may be a Geiger counter or ionization chamber commonly used in making gamma ray well surveys. The instrument is suspended by cable 12, over which indications of the radioactivity are obtained electrically and recorded in any known manner. Cable 12 may pass through a lubricator at the top of tubing 13 so measurements may be made while the well is producing. Known devices are used to determine the depth of unit 16. Measurements of the radioactive intensity are made over the entire length of the strainer, and the results of the examination are customarily obtained in the form of a graph, such as is indicated in Fig. 2.

In Fig. 2, numeral 19 represents a chart or record as obtained by a conventional recording means such as is used for gamma ray well logging. Along one side a scale 20 shows the depth of the detecting instrument 16. A curve 21 whose arbitrary zero line is indicated by dotted line 22 shows the measured intensity of radioactivity produced by the material in strainer grooves 18 (Fig. 1). The curve 21 shows a high value where the radioactive material in the grooves has not been disturbed, while the points of lowest intensity will be found opposite the water producing zone or zones. As illustrated in Fig. 2, the curve 21 shows high radioactive intensity opposite formations 4 and 5, indicating that these are oil producing horizons, while opposite the formation 6 a low value of radioactivity is observed, indicating that this formation produced water which removed the radioactive material from the adjacent section of the strainer. In some cases a formation may produce both oil and water. Thus opposite the top of formation 8, for example, the curve shows an intermediate intensity 23 thereby indicating only a partial removal of the water-soluble radioactive material. This means that the upper part of this formation produces a relatively smaller amount of water. The gradual decrease in radioactive material observed on the screen progressing toward the bottom of formation 8 indicates that there is a gradual increase in the amount of water produced. Thus one may determine that formation 8 produces a small amount of water at its top and a large amount of water at the bottom.

Once the water sources have been located by the method of this invention, any known suitable steps may be taken to stop the flow of water. The water producing horizons may be cemented off, or selective plugging operations may be performed on horizons which are indicated as producing mixtures of oil and water. One of the particular advantages of this process is that the water producing formation may be located and in many cases treated without removing the strainer, an operation which is often rather costly.

In the case of oil wells which are producing water, similar information may be obtained by lowering into the well opposite the producing

formation, a screen equipped with a suitable packer coated or impregnated with a water-soluble radioactive material or mixture, and after producing the well for sufficient time, examining the screen with a detecting element to discover which portion has been washed by water. The examination of the screen may take place either in the well or at the surface. In order to eliminate the solvent effect of any water which may have accumulated in the bottom of the well during previous production, it would be desirable to displace the fluid in the well with dry oil just before making a test.

The method and apparatus of my invention may alternatively be used for detecting the point of entry of oil into a well by using an oil-soluble radioactive material on the strainer. For holding the radioactive material in this case a matrix may be used which has suitable solubility characteristics in oil. Suitable oil soluble materials are naphthalene, anthracene, or elemental sulphur. The radioactive substance may also be embedded in oil resistant rubber such as Neoprene and Duprene, which are only slightly soluble in oil.

My invention may be further used to detect both the points of entry of water and the points of entry of oil by means of a single strainer in one production test. This is done by filling alternate grooves 18 on the strainer with water-soluble and with oil-soluble radioactive material, the radioactive materials being so chosen that their emanations are distinctive in order that they may be distinguished by the instrument 16. This may be done by using for one material a radioactive compound which gives off relatively soft gamma rays, while for the other material a radioactive compound which gives off hard gamma rays may be used. After the production test a gamma ray log is first run using an ordinary ionization chamber in unit 16, and then repeated with a shield around the unit 16. The first curve then indicates the presence of both materials and the second indicates presence of only the hard ray producing material. By comparing these curves with the known initial distribution of the radioactive materials one may easily deduce where oil is produced and where water is produced. Obviously also where neither of the two materials are removed the formation is either barren or produces gas.

The radioactive matrix material chosen should have a solubility depending on the duration of the production test made while the screen or strainer is in the well. Furthermore, artificially radioactivated materials may be used provided only that their lifetime be sufficiently long to permit of making the necessary production and inspection tests.

My invention may also be used when it is desired to locate highly permeable horizons which by-pass or short circuit the input fluid used in water flooding operations. Such horizons, sometimes called "thief sands" are encountered in input wells and may be located by setting a special strainer similar to that shown in Fig. 1. Fluid, usually water in this case, is pumped down the well and flows out through the strainer into the producing formations. The water-soluble radioactive material used in grooves 18 should for this purpose be only slightly soluble, so that it is not completely removed by the water flowing out into the formation. The degree of removal of radioactive material may be ascertained from the radioactive intensity observed on examination

with instrument 16 as indicated on curve 21, Fig. 2. A slight decrease in observed radioactive intensity results from only a slight removal of material indicating that the adjacent formation is taking only a small flow of water, while a large decrease results from a larger removal of radioactive material indicating that this formation is taking a large flow of water. Any "thief" formations taking excessive water may then be plugged or sealed by known methods.

Other well known variations of the equipment in the well may be made without affecting my invention. The casing 10, Fig. 1, may for example extend all the way to the bottom of the hole and may have perforations along its length opposite the producing formations. As another example the strainer may be eliminated and the outside of the perforated casing may contain the radioactive material that indicates the nature of the produced fluids.

While I have shown the radioactive material placed in external grooves on the strainer, such material may be otherwise disposed on the strainer. The essential feature is that its position may be detected and that it come in contact with the fluid being produced from the adjacent formation. The distribution of radioactive material is advantageously made uniform along the length of the strainer, but any known distribution may be used as well. If the operator suspects loss of material while running the strainer into the hole, an initial test with the gamma ray instrument may be made after the strainer is in place and before production is begun.

Other radioactive materials may be substituted for those mentioned, e. g. inorganic or organic derivatives of radioactive elements mixed with a suitable binder may be employed as the indicating substance.

What I claim is:

1. A method of determining the source of fluid entering a well which comprises placing in the well opposite the producing formation a known configuration of solid radioactive material removable by the produced fluid, allowing the well to produce for a period sufficient to remove a portion of said radioactive material and subsequently determining the distribution of radioactive material remaining in the well.
2. A method of determining the source of fluid entering or leaving a well which comprises placing in the well a known configuration of solid radioactive material removable by the fluid flow, permitting the well fluid to flow for a sufficient time to remove a portion of said radioactive material and subsequently measuring the distribution of radioactive material remaining in the well.
3. A method of determining the source of fluid entering a well which comprises placing in the well opposite the producing formation a known configuration of solid radioactive material removable by the produced fluid, allowing the well to produce for a period sufficient to remove a portion of said radioactive material and examining the well with an instrument sensitive to emanations from the radioactive material to determine the regions in which said radioactive material has been removed by the fluid.
4. An apparatus for determining the source of any fluid being produced in a well comprising a strainer having associated therewith a known distribution of radioactive material soluble in said fluid, means for producing the well and means for examining the strainer for radioactive emanations to determine the regions in which said ra-

radioactive material has been removed by the fluid.

5. An apparatus for producing a well and determining the source of water being produced comprising a strainer having on its outer surface a substantially uniform distribution of water-soluble radioactive material, means for producing the well and means for examining the strainer for radioactive emanations to determine the regions in which said radioactive material has been removed.

6. An apparatus for simultaneously producing a well and determining the source of water being produced comprising a strainer initially having a substantially uniform distribution of water-soluble radioactive material thereon, means for restricting external axial flow of fluid, means for producing the well and means for examining the strainer for radioactive emanations to determine the regions in which said radioactive material has been removed.

7. An apparatus for simultaneously producing a well and determining the source of oil being produced comprising a strainer initially having a substantially uniform distribution of oil-soluble

radioactive material thereon, means for producing the well and means for examining the strainer for radioactive emanations to determine the regions in which said radioactive material has been removed.

8. An apparatus for determining the source of components of a well effluent comprising a strainer initially having thereon a known distribution of separate distinguishable radioactive materials 10 each soluble in a component of the effluent, means for producing the well and means for examining the strainer for each of the radioactive materials to determine the regions in which each radioactive material has been removed.
